HYDRAULIC CONTROL SYSTEM

Howard F. Lawrence, Philadelphia, Pa., assignor
to American Engineering Company, Philadel-
phia, Pa., a corporation of Pennsylvania

Application March 24, 1937, Serial No. 132,689

7 Claims. (Cl. 60—52)

This invention relates to hydraulic control systems, and more particularly to systems employed to reverse the direction of discharge of pumps when the pressure developed thereby exceeds a predetermined value.

One object of the present invention is to provide a generally improved and simplified control system of the stated character which is fully automatic in operation.

Another object is to provide a system of the stated character wherein the pump controls are positively actuated to effect a reversal of the discharge thereof.

A further and more specific object is to provide in a fluid system including a high pressure pump for actuating feeding rams, a control device which automatically and positively effects reversal of the discharge of the pump when the rams reach their limit of travel in either direction.

Other and further objects will become apparent as the description of the invention progresses.

Of the drawings:

Fig. 1 is a plan view partly in section and diagrammatic in part, showing a general assembly of the hydraulic control system comprising the present invention.

Fig. 1a is a partial schematic view partly in section and with certain parts removed to show the structure of the entire assembly constituting the present invention.

Fig. 2 is a side view partly in section, of the fluid motor for actuating of the pump controls and the valves controlling the operation thereof.

Fig. 3 is an end view of the mechanisms shown in Fig. 2.

Fig. 4 is a sectional view taken substantially along line 4—4 of Fig. 3.

Fig. 5 is a sectional view taken substantially along line 5—5 of Fig. 2.

Fig. 6 is a sectional view taken substantially along line 6—6 of Fig. 2.

Fig. 7 is a sectional view taken substantially along line 7—7 of Fig. 2.

Fig. 8 is a diagrammatic view partly in section of an alternative construction, and

Fig. 9 is a sectional view taken substantially along line 9—9 of Fig. 8.

Referring to the drawings, the numeral 1 indicates a variable stroke, reversible discharge pump connected in the present instance by main pipes 2 and 3 and branch pipes 5 and 4 to the opposite ends of a series of cylinders 6. A piston

1 operates in each cylinder 6, and is connected in any suitable manner in the present instance to a ram which feeds materials from hoppers 8 to any desired receiving means (not shown). Pump 1 may be of the general type shown and described in United States Patent No. 1,077,979, and the drive shaft 9 thereof is connected by any suitable coupling 10 to the armature shaft 11 of an electric motor 12. Pump 1 and motor 12 are rigidly secured to a makeup or supply tank 13, from which makeup fluid may be drawn into the system through pipes 14 and 15 connected respectively to main pipes 2 and 3.

The sliding blocks 18 of pump 1 which, as is well known in the art, control the quantity, as well as the direction of discharge of the pump, are actuated by means of a fluid motor 19. Fluid motor 19 comprises a cylinder 20 having a double-acting piston 21 operating therein, and is secured by any suitable means, such as bolts 20 to one side of the casing 23 of pump 1. Piston rod 24 of piston 21 extends through a bearing 25 provided at one end of cylinder 20, and the free end thereof is secured to a crosshead 26, as shown more particularly in Figs. 1 and 2. Crosshead 26 has secured to the opposite ends thereof the outer ends of a pair of rods 27 and 28. These rods extend through suitable bearings provided in casing 23, and are secured at their inner ends to the sliding blocks 18. The operation of piston 21 is controlled by a valve mechanism indicated generally by the numeral 29. Valve mechanism 29 is mounted upon a supporting bracket 30 extending laterally from the upper side of cylinder 20, and is secured thereto by bolts 31, as shown particularly in Figs. 2 and 3. Valve mechanism 29 comprises a casing 32 having a substantially vertical portion 33, and a substantially horizontal portion 34. The vertical portion 33 of casing 32 has provided therein a pair of cylindrical chambers 35 and 36, which are connected at the lower ends thereof by a passage 37, and at a point intermediate the ends thereof by a second passage 38. Chambers 35 and 36 have operating therein valves 39 and 40, respectively. Valve 39, as shown more particularly in Fig. 4, comprises a pair of valve heads 41 and 42 connected by a reduced portion 43. Extending upwardly from valve head 42 is a slightly reduced portion 44, the upper end of which engages an annular shoulder 45 provided in vertical portion 33 to limit the upward movement thereof. Extending upwardly from reduced portion 44 is a further reduced portion 46 which forms a neck, and extending upwardly from por-

tion 46, is a slightly enlarged guiding portion 47 which makes sliding contact with an aperture 48 provided at the upper end of portion 33. Fig. 4 shows the position of the parts when in normal 5 position. The left hand end of portion 33 of the casing 32 has provided therein an upper port 49, an intermediate port 50, and a lower port 51. Ports 50 and 51 are normally closed by plugs 52 and 53 respectively. Valve 40 operating in chamber 10 36 is similar in construction to valve 39, and also consists of a pair of valve heads 54 and 55 connected by a reduced portion 56. The upper end of valve 40 has a slightly reduced portion 57 which, when valve member 40 is in its upper 15 position, engages an annular shoulder 58 provided near the upper end of portion 33. Valve 40 also has a further reduced portion 59 and a slightly enlarged upper portion 60 extending upwardly therefrom which extends through a guiding 20 aperture 61 provided at the upper end of portion 33. The upper end of casing 33 is provided with a cap member 62, which is secured thereto by any suitable means such as by bolts 63. The right hand end (Fig. 4) of vertical portion 33 has 25 also provided therein an upper port 64, an intermediate port 65, and a lower port 66. Ports 65 and 66 are normally closed by plugs 67 and 68 respectively.

As shown more particularly in Fig. 6, the substantially horizontal portion 34 of casing 32 is provided with a transversely extending cylindrical chamber 69, in which operates a valve member 70. Valve member 70 consists of a pair of valve heads 71 and 72, which are connected by 30 means of a reduced portion 73. Portion 34 has secured to the ends thereof a pair of extensions 74 and 75. As shown in Fig. 6, extension 74 is secured to portion 34 by bolts 74', and has provided therein a cylindrical bore consisting of an 35 enlarged portion 76 and a reduced portion 77. The reduced portion 77 has a smaller diameter than chamber 69, and the inner end 78 of extension 74 forms an abutment for valve 70 when the latter has moved to its extreme left hand position. Chamber 77 has operating therein a piston 79, the reduced portion 80 thereof engaging the left hand end of valve head 71. A plug 81 closes the left hand end of extension 74.

Extension 75 is of similar construction and is 40 secured to the right hand end of portion 34 by means of bolts 82. Extension 75 is also provided with a central bore consisting of an enlarged portion 83, and a reduced portion 84 in line with chamber 69. A plug 85 closes the outer end of extension 75. The reduced portion 84 has provided therein a piston 86, the reduced portion 87 of which engages the right hand end of valve head 72.

Extensions 74 and 75 have provided at one side 45 thereof ports 88 and 89 which communicate respectively with the enlarged portions 76 and 83 thereof. Portion 34 has also provided therein a pair of spaced ports 90 and 91 communicating with chamber 69. Chamber 69 is also connected 50 intermediate the ends thereof to passage 37 by means of a communicating passage 92.

Vertical portion 33 of casing 32 has also provided at one side thereof a pair of ports 93 and 94 which communicate respectively with chambers 35 and 36 intermediate the ends thereof. As shown in Figs. 2 and 5, when valves 39 and 40 are in their upper position of adjustment, ports 93 and 94 are partially covered by the lower ends of valve heads 42 and 55. Ports 93 and 88 55 are connected by means of a pipe 95. Ports 94

and 89 are similarly connected by a second pipe 96. Port 90 provided in portion 34 is connected to the inlet port 97 provided at the left hand end of cylinder 20 by means of a pipe 98. Port 91 of portion 34 is likewise connected to the inlet port 99 provided at the right hand end of cylinder 20 by means of a second pipe 100. Port 49 provided at the upper left hand side of vertical portion 33 is connected to the main pipe 3 by a pipe 101. Port 64 provided at the upper right hand side of vertical portion 33 is likewise connected to main pipe 2 by means of a pipe 102. The lower end of casing 32 is provided with another port 103, which communicates with passage 37, as shown in Figs. 4, 5 and 6. This port is connected by 15 means of a pipe 104 to a small pump 105 driven by motor 12 through a chain and sprocket mechanism 106. Fluid is drawn into pump 105 from makeup tank 13 through a pipe 107. Pipe 104 also has connected thereto any suitable relief 20 valve 108, which in turn is connected to makeup tank 13 by means of a pipe 109. Relief valve 108 is normally maintained upon its seat by means of a spring 108', the pressure of which may be varied by an adjusting screw 108''. It 25 therefore will be observed that by providing an adjustable relief valve of this type reversing of pump 1, and consequently of motors 6 may be effected at different predetermined pressures.

From the foregoing description it is seen that 30 the upper ends of valve heads 42 and 55 of valves 39 and 40 respectively are constantly connected to the pressure in main pipes 2 and 3 leading from pump 1. It is also seen that the lower ends of valve heads 41 and 54 of valves 39 and 40 35 respectively, are constantly subjected to pressure developed by pump 105. The effective areas of valve heads 41 and 54 are much greater than the effective areas of valve heads 42 and 55, and consequently, valves 39 and 40 will be retained 40 in their uppermost position, shown in Fig. 4, throughout a predetermined operating range. However, in the event the pressure in the main pipes 2 and 3 operating against the upper ends of valve heads 42 and 55 is sufficiently great to 45 overcome the pressure operating at the lower ends of valve heads 41 and 54, valves 39 and 40 will be moved downwardly to uncover ports 93 and 94, as will appear more fully hereinafter.

It will also be observed that when valve 70 is 50 in a central position, ports 90 and 91 will be covered by valve heads 71 and 72, respectively, and consequently the inner ends of said valve heads will be subjected to equal pressures, and no movement will be imparted thereto. Under 55 these conditions, when the pressure developed by small pump 105 becomes sufficiently great, relief valve 108 will open to permit the discharge of said pump to pass to makeup tank 13.

As previously described, a passage 38 connects 60 vertical chambers 35 and 36 intermediate the ends thereof. This passage is also connected to a port 110, which in turn is connected to a vertical passage 111, which extends from port 110 to the upper end of vertical portion 33. By this 65 means any leakage of fluid past the guiding portions 47 and 60 of valves 39 and 40 will flow into vertical passage 111. Port 110 is connected to makeup tank 13 by means of a pipe 112, and consequently this leakage will drain back to make- 70 up tank 13.

Casing 32 also has provided therein a pair of 75 passages 113 and 114 which connect the opposite ends of chamber 69 of horizontal portion 34 with ports 50 and 65 of vertical portion 33. Thus, 75

any fluid leaking past valve heads 71 and 72 of valve member 70 and the pistons 79 and 86 will be forced through these passages and thence into the portion of chambers 35 and 36 disposed between valve heads 41, 42 and 54, 55. Such fluid will then pass through passage 38, port 110, and thence to makeup tank 13 through pipe 112.

Referring to Fig. 2, it will be noted that any fluid from cylinder 20 leaking between piston rod 24 and bearing 25 thereof enters a pocket 115 connected to an outlet port 116 by a communicating passage 117. Port 116 is connected to make-up tank 13 by a pipe 118. Thus, any leakage between piston rod 24 and its bearing 25 will also flow to makeup tank through pocket 115, communicating passage 117, and pipe 118.

Mechanism is also provided for varying the stroke of pump 1 and thus the discharge thereof. Referring to Fig. 1, it will be observed that the left hand sides of sliding blocks 18 have secured thereto the inner ends of a pair of guide rods 120 and 121. The outer ends of these rods are secured to a crosshead 122 having a central aperture through which extends a shaft 123. Shaft 123 is journaled in an abutment plug 124 which makes threaded engagement with the vertical wall 125 of a bracket 126 secured in any suitable manner to the left hand side of pump 1. The inner end of shaft 123 is journaled in a bearing provided in the wall 127 of pump casing 23. Shaft 123 has provided thereon a pair of right and left hand threaded portions 128 and 129 which make threaded engagement with a pair of non-rotatable blocks 130 and 131 respectively, mounted in any suitable manner for axial movement toward and from cross-head 122. A hand wheel 132 is secured to the outer end of shaft 123 for rotating the latter. Thus, upon movement of hand wheel 132 in one direction blocks 130 and 131 will move away from each other, thereby increasing the distance between said blocks and crosshead 122, and consequently lengthening the stroke of pump 1 when sliding blocks 18 are adjusted by motor 19. On the other hand, when hand wheel 132 is rotated in the reverse direction blocks 130 and 131 are moved toward each other to decrease the stroke. When blocks 130 and 131 are brought into engagement with crosshead 122 the sliding blocks 18 are centered and consequently the pump is held on neutral stroke. Mechanisms of this type for varying the stroke of a pump are well known in the art, and for a more detailed description thereof reference may be had to United States Patent No. 1,656,034.

From the foregoing description it is thought that the operation of my hydraulic control system is apparent. However, in order to correlate the various elements thereof, a brief résumé of the operation thereof will now be given.

Let us assume hand wheel 132 has been actuated in such a direction as to effect movement of blocks 130 and 131 away from each other, and valve member 70 has been actuated to the position shown in Fig. 6. Fluid from pump 105 will now enter the right hand end (Fig. 2) of motor 19 through pipe 104, passages 37 and 92, chamber 69 and pipe 100, causing piston 21, and consequently sliding blocks 18 of pump 1, to move to the left. Pump 1 will now deliver fluid under pressure to main pipe 2 and suction to main pipe 3. Fluid under pressure will now pass to the outer ends of cylinders 6 through branch pipes 5, causing the pistons 7 to move in the feeding direction. The fluid at the other ends of cylinders 6 will be returned to pump 1 through branch pipes

4 and main pipes 3. Pistons 7 will now continue their movement in the feeding direction until they reach their limit of travel whereupon the pressure developed by pump 1 will rapidly increase. This pressure is communicated to the upper end of valve 40 through pipe 102, and when the pressure so impressed exceeds that delivered by pump 105, which, it will be remembered, is at all times directed against the lower end of valve 40, the latter will move downwardly to uncover port 94. When this occurs fluid pressure is delivered against the right hand end (Fig. 6) of piston 86, which in turn actuates valve member 70 to the left. When this occurs communication is established between the left hand end of motor 19 and pump 105, through pipe 104, passages 37, and 92, chamber 69, port 90, and pipe 98 whereby piston 21 moves to the right to reverse the discharge of pump 1. When this occurs fluid under pressure will be delivered to pipe 3 and suction to pipe 2, whereupon pistons 7 operating in cylinders 6 will be actuated in the return direction. When pistons 7 reach the limit of their travel in this direction pressure again builds up in the system, which pressure is communicated to the upper end of valve 39. When this pressure exceeds that imposed against the lower end of valve 39 by pump 105 as aforesaid, valve 39 will move downwardly to uncover port 93. The pressure in pipe 3 is now impressed against the left hand end of piston 79, causing valve 70 to be shifted to the right, as shown in Fig. 6. Fluid from pump 105 now passes through passages 37, communicating passage 92, chamber 69, port 91, and thence to the inlet passage 99 of motor 19, through pipe 100, causing piston 21 to again shift to the left. This procedure continues to effect reversing of pistons 7 at the end of each operation thereof in both the feeding and return directions. Upon a reduction in the pressure operating against the upper ends of valves 39 and 40 when sliding blocks 18 pass the neutral position, said valves are actuated to their upper positions of adjustment by the pressure imposed at the lower ends thereof by pump 105, thus interrupting the fluid connections between ports 88—93, and 89—94. When valve member 70 is shifted in either direction the fluid at the low pressure side thereof is forced to exhaust pipes 95 or 96, valve chambers 35 and 36, passage 38, port 110 and pipe 112, since it will be remembered that the lower ends of valve heads 42 and 55 only partially cover ports 93 and 94 respectively, when valve members 39 and 40 are in their upper position of adjustment. Any leakage past valve heads 71 and 72 and pistons 79 and 86 will enter passages 113 or 114, as the case may be, and will be directed to ports 59 or 65 through the portions of chambers 35 and 36 disposed between the valve heads of valve members 39 and 40 operating therein, and intermediate passage 38. Such fluid will then drain back to makeup tank 13 through pipe 112. In a similar manner any fluid leaking past the guide extensions 47 and 60 of valve members 39 and 40 respectively, will flow into vertical passage 111 and thence to makeup tank 13 through port 110 and pipe 112. Should valve member 70 for any reason assume a central position, it may be manually adjusted to either of its effective positions upon removal of plug 81 or 85. To prevent excessive pressures in the system, especially during reversing periods of the stroke controls of pump 1, main pipes 2 and 3 have provided therein relief valves 134 and 135 respectively, which in turn are connected to makeup tank 13 by pipes 136 and 137.

Figs. 8 and 9 show the invention applied to a pump 140 wherein the discharge thereof is controlled by a valve 141. Pump 140 is operated by electric motor 142 through any suitable coupling 143, and receives its fluid from a makeup or supply tank 144 through an intake pipe 145. Pump 140 discharges fluid under pressure to pipe 146 connected to a port 147 communicating with the central cylindrical chamber 148 of valve 141. Valve 141 also has provided therein a pair of spaced ports 149 and 150, to which one end of a pair of pipes 151 and 152 respectively, are connected. Pipes 151 and 152 are connected by branch pipes 153 and 154, to the opposite ends of the cylinders 155 of a pair of fluid motors 156. Cylinders 155 have pistons 157 operating therein to which feeding rams may be connected in any suitable manner. Valve 141 has also provided therein a port 158 at one end thereof which is connected to makeup tank 144 by means of a pipe 159. The reduced portions 160 and 161 at the opposite ends of chamber 148 are connected by means of a pipe 162. Valve 141 has provided therein a valve element 163 having a pair of valve heads 164 and 165 connected by a reduced portion 166. Valve element 163 has a stem 167 secured thereto, which extends through the end wall 168 of valve 141. The opposite end of valve stem 167 has secured thereto a piston 169 which operates in the cylinder 170 of a fluid motor 171 secured in any suitable manner, such as by bolts 172 to the casing of valve 141. The head end 173 of motor 171 is connected to a normally closed port 174 of a control valve 175 by means of a pipe 176. The other end of motor 171 is connected to a second port 177 of control valve 175 by means of a second pipe 178. Control valve 175 has provided therein a pair of cylindrical chambers 179 and 180, which are connected at one end thereof by a passage 181 and ports 182 and 183. Chamber 179 has provided therein a valve element 184 consisting of a pair of valve heads 185 and 186 connected by a reduced portion 187. The upper end of valve element 184 has secured thereto a reduced guiding extension 188 which extends through a guiding aperture 189 provided at the upper end of control valve 175. Chamber 180 also has provided therein a similarly constructed valve element 190 consisting of a pair of valve heads 191 and 192 connected by a reduced portion 193. One end of valve 190 also has secured thereto a reduced guiding extension 194 which extends through a second guiding aperture 195 in line with chamber 180. The upper end of chamber 179 is connected to pipe 152 by means of a pipe 196. The upper end of chamber 180 is connected to pipe 151 by a pipe 197. Passage 181 is connected to a small pump 198 by means of a pipe 199. Pump 198 is connected to shaft 200 of pump 140 by a chain 201 and sprocket mechanism 201, and fluid is drawn into said pump 198 from makeup tank 144 through a pipe 202. Pipe 199 has provided therein an adjustable relief valve 203 which in turn is connected to makeup tank 144 by means of a pipe 204. Relief valve 203 may be of the general type shown at 108 in Fig. 1.

The cylindrical chambers 179 and 180 of control valve 175 are interconnected intermediate the ends thereof by means of a transverse passage 205. A second passage 206, extending substantially at right angles to passage 205, extends from the latter to the outside of the casing of valve 175, and a pipe 207 connects passage 206 with makeup tank 144. Any fluid leaking past the upper guide portions 188 and 194 of valve members 184 and

190 respectively, flows into a vertical passage 208 which extends from the upper end of valve 175 to passage 206. It will be observed that when valve members 184 and 190 are in their uppermost position, the ports 177 and 174 are only partially covered by the valve heads 185 and 191 respectively. Thus, when valve 190 is in the position shown in Fig. 8, and fluid from pipe 151 flows through pipe 197, port 174 and pipe 176 to the head end of piston 169, the fluid at the other end of cylinder 170 will pass through pipe 178, port 177, the annular chamber between valve heads 185 and 186, transverse passage 205, passage 206, and pipe 207, to makeup tank 144. On the other hand, when valve 190 is in its upper position, and valve 184 is in its lower position, fluid from the head end of cylinder 170 will flow to makeup tank 144 through pipe 176, port 174, the chamber between valve heads 191 and 192, transverse passage 205, passage 206, and pipe 207.

From the foregoing description it is seen that port 147 of valve 141 at all times is disposed between valve heads 164 and 165. When the parts are in the position shown in Fig. 8 fluid from pump 140 enters the central chamber 148 of valve 141 through pipe 146 and port 147. Fluid then flows to the right hand ends of cylinders 155 through pipe 151, causing pistons 157 to move to the left. Fluid at the left hand end of cylinders 155 then flows to makeup tank through pipes 154, 152, port 150, chamber 148, the reduced portion 161 thereof, and pipe 159. When pistons 157 reach the limit of their travel in this direction, pressure builds up in pump 140. This pressure is transmitted to the upper end of valve member 190 through pipe 197. When this pressure is sufficient to overcome that imposed against the lower end of said valve member by the small pump 198, valve element 190 moves downwardly, thereby uncovering port 174 to permit fluid under pressure to enter the head end of motor 170. Piston 169 of motor 171 now actuates valve element 166 to its other extreme position of adjustment, and thereby establishes communication between pump 140 and pipe 152. Fluid now enters the left hand end of cylinders 155, thereby causing the pistons 157 operating therein to move to the right. The fluid at the right hand end of cylinders 155 will now flow back to makeup tank through pipes 153, 151, port 149, chamber 148, reduced portion 160, pipe 162, reduced portion 161, and pipe 159. When pistons 157 reach the limit of their travel in this direction, the pressure developed by pump 140 again builds up. Pipe 152, it will be remembered, is connected to the upper end of chamber 179 by means of pipe 196, and when this pressure exceeds that imposed upon the lower end of valve member 184 by small pump 198, said valve element will move downwardly to uncover port 177. When this occurs, fluid will enter the piston rod end of motor 171 through port 177 and pipe 178, causing piston 169 to actuate valve element 163 to the position shown in Fig. 8. Fluid from pump 140 will now again enter the right hand ends of cylinders 155, causing the pistons 157 operating therein to move to the left. This procedure is repeated to effect reverse operations of pistons 157 when they reach their limit of travel in either direction.

It therefore is seen that simplified, as well as highly improved hydraulic control systems have been provided which positively reverse the discharge of the pump when the pressure in the system exceeds a predetermined value. In the embodiment shown in Figs. 1 to 7 it will also be noted

that the joints between extensions 74 and 75 and the horizontal portion 34 of casing 32 are not subjected to high pressures because of passages 113 and 114 which connect the opposite end of chamber 69 with exhaust. The same is true of the joints between the upper end of vertical portion 33 of casing 32 and cap member 62 because of passage 111 which connects the end of said portion with exhaust. As a result heavy packings 10 are unnecessary to prevent leakage of fluid from the system. It also is seen that the system is constantly filled with fluid and that any air drawn into the same escapes to exhaust with the leakage through passages 113 or 114 and the passages 15 communicating therewith, as previously described.

While the embodiments herein shown and described are admirably adapted to fulfill the objects primarily stated, it is to be understood that 20 the invention is not to be limited thereto, since it may be embodied in other forms, all coming within the scope of the claims which follow.

What is claimed is:

1. In a device of the class described, the combination of a reversible discharge pump, motor means, piping connecting said motor to said pump, a fluid motor for actuating said pump to reverse the discharge thereof, an auxiliary pump for actuating said fluid motor, a shiftable valve for controlling the operation of said fluid motor, normally inoperative means operated by the fluid pressure developed in said reversible discharge pump for adjusting said valve, valve means for controlling the operation of said normally inoperative means, means connecting one end of said valve means to the pressure side of said reversible discharge pump, and means connecting the other end of said valve means to the pressure side of said auxiliary pump, whereby when the pressure imposed upon said valve means by said reversible discharge pump exceeds that imposed thereon by said auxiliary pump, said valve means operates to render said normally inoperative means operative to effect adjustment of said shiftable valve.

2. In a device of the class described, the combination of a reversible discharge pump, motor means, piping connecting said motor means to said pump, a fluid motor for actuating said pump to reverse the discharge thereof, an auxiliary pump for actuating said fluid motor, a shiftable valve for controlling the flow of fluid from said auxiliary pump to said fluid motor, normally inoperative servomotor means operated by fluid pressure developed by the reversible discharge pump for actuating said shiftable valve to different positions of adjustment, a valve mechanism comprising a pair of valve elements for controlling the operation of said servomotor means, means connecting one end of one of said valve elements to the pressure side of said reversible discharge pump when the latter is discharging fluid in one direction, means connecting one end of the other of said valve elements to the pressure side of said reversible discharge pump when the latter is discharging fluid in the reverse direction, and means connecting the opposite end of each of said valve elements to the pressure side of said auxiliary pump, whereby when the pressure imposed upon either of said valve elements by said reversible discharge pump exceeds that imposed thereon by said auxiliary pump the said valve element subjected to such pressure operates to render said servomotor means operative to effect adjustment of said shiftable valve.

3. In a device of the class described, the com-

bination of a main pump, a double-acting fluid motor operated by the said main pump, means controlling the flow of fluid from said pump to said fluid motor, a servomotor for actuating said controlling means, an auxiliary pump for actuating said servomotor, a shiftable valve for controlling the operation of said servomotor, normally inoperative means operable by the fluid pressure developed in said main pump for adjusting said shiftable valve, valve means for controlling the operation of said normally inoperative means, means connecting one end of said valve means to the pressure side of said main pump, and means connecting the other end of said valve means to the pressure side of said auxiliary pump, whereby when the pressure imposed upon said valve means by said main pump exceeds that imposed thereon by said auxiliary pump said valve means operates to render said normally inoperative means operative to effect adjustment of said shiftable valve.

4. In a device of the class described, the combination of a main pump, a double-acting fluid motor operated by the said main pump, means controlling the flow of fluid from said pump to said fluid motor, a servomotor for actuating said controlling means, an auxiliary pump for actuating said servomotor, a shiftable valve for controlling the operation of said servomotor, normally inoperative means operable by the fluid pressure developed in said main pump for adjusting said shiftable valve, valve means for controlling the operation of said normally inoperative means, means connecting one end of said valve means to the pressure side of said main pump, means connecting the other end of said valve means to the pressure side of said auxiliary pump, whereby when the pressure imposed upon said valve means by said main pump exceeds that imposed thereon by said auxiliary pump said valve means operates to render said normally inoperative means operative to effect adjustment of said shiftable valve, and means for varying the pressure developed by said pump.

5. In a device of the class described, the combination of a main pump, a double-acting fluid motor operated by said main pump, means for controlling the flow of fluid from said pump to said motor, a servomotor for actuating said controlling means, an auxiliary pump for actuating said servomotor, a shiftable valve for controlling the operation of said servomotor, motor means operable by the fluid pressure developed in said main pump for adjusting said shiftable valve, valve means for controlling the operation of said motor means, means connecting one end of said valve means to the pressure side of said main pump, and means connecting the other side of said valve means to the pressure side of said auxiliary pump, whereby when the pressure imposed upon said valve means by said main pump exceeds that imposed thereon by said auxiliary pump, said valve means operates to connect said motor means for operation to effect adjustment of said shiftable valve.

6. In a device of the class described, the combination of a main pump, a double-acting fluid motor operated by said pump, means controlling the flow of fluid from said main pump to said fluid motor, a servomotor for actuating said controlling means, an auxiliary pump for actuating said servomotor, a shiftable valve for controlling the flow of fluid from said auxiliary pump to said servomotor, motor means operable by the fluid pressure developed by said main pump for actu-

- ating said shiftable valve to different positions of adjustment, a valve mechanism comprising a pair of valve elements for controlling the operation of said motor means, means for alternately connecting one end of each of said elements to the pressure side of said main pump, and means connecting the opposite end of each of said elements to the pressure side of said auxiliary pump, whereby when the pressure imposed upon either of said valve elements by said main pump exceeds that imposed thereon by said auxiliary pump, the said valve element subjected to such pressure operates to render said motor means operative to effect adjustment of said shiftable valve.
7. In a device of the class described, the combination of a main pump, a double-acting fluid motor operated by said pump, means controlling the flow of fluid from said main pump to said fluid motor, a servomotor for actuating said controlling means, an auxiliary pump for actu-

ating said servomotor, a shiftable valve for controlling the flow of fluid from said auxiliary pump to said servomotor, motor means operable by the fluid pressure developed by said main pump for actuating said shiftable valve to different positions of adjustment, a valve mechanism comprising a pair of valve elements for controlling the operation of said motor means, means for alternately connecting one end of each of said elements to the pressure side of said main pump, 10 means connecting the opposite end of each of said elements to the pressure side of said auxiliary pump, whereby when the pressure imposed upon either of said valve elements by said main pump exceeds that imposed thereon by said auxiliary pump, the said valve element subjected to such pressure operates to render said motor means operative to effect adjustment of said shiftable valve, and means for varying the pressure developed by said auxiliary pump. 15
